C. Snow & Co.

UNITED STATES PATENT OFFICE.

CEPHAS GILBERT, OF BRANFORD, FLORIDA.

ANTIREFILLING BOTTLE.

SPECIFICATION forming part of Letters Patent No. 576,263, dated February 2, 1897.

Application filed February 20, 1896. Serial No. 580,028. (No model.)

To all whom it may concern:

Be it known that I, CEPHAS GILBERT, a citizen of the United States, residing at Branford, in the county of Suwannee and State of Florida, have invented a new and useful Antirefilling Bottle, of which the following is a specification.

The invention relates to improvements in antirefilling bottles.

10 The object of the present invention is to improve the construction of antirefilling bottles, to increase their simplicity and efficiency, and to provide an inexpensive one which will effectually prevent the introduction of a liquid into it after it has received its contents, and which will be entirely useless after its original contents have been decanted.

15 The invention consists in the construction and novel combination and arrangement of parts hereinafter fully described, illustrated in the accompanying drawings, and pointed out in the claim hereto appended.

20 In the drawings, Figure 1 is an elevation of a portion of a bottle constructed in accordance with this invention. Fig. 2 is a vertical sectional view of the same. Fig. 3 is a detail view of the ball-valve.

25 Like numerals of reference designate corresponding parts in all the figures of the drawings.

30 I designates a bottle provided on the interior of its neck with an annular rib 2, formed by creasing or constricting the neck when the glass is in a heated condition and providing an exterior annular groove 3. The rib 2 has its upper inclined face ground to form a valve-seat 4 and receiving a ball-valve 5, constructed of glass or any other suitable material and having a limited movement to and from the 35 valve-seat to permit the contents of the bottle to be decanted when the bottle is in an inverted position. When the bottle is arranged in an upright position, the ball-valve fits snugly on the seat 4, closing the neck of the bottle and effectually preventing the introduction of a liquid into the latter.

35 The ball-valve is retained in proper position in the neck of the bottle by a pair of spring-arms 6, provided with straight parallel upper portions 7 and having oppositely-disposed outwardly-extending V-shaped lower

portions 8, lying below the rib 2 and adapted to engage the lower inclined face 8 thereof, to prevent the ball from leaving the neck of the bottle. The spring-arms are preferably constructed of a single piece of resilient material having a substantially U-shaped upper connecting portion 9, arranged in a slot or opening of the ball-valve, as illustrated in Fig. 2 of the accompanying drawings.

55 After the bottle has received its original contents the ball-valve is introduced into the neck and the V-shaped lower portions are adapted to spring inward automatically when they engage the valve-seat, to pass the same, and to permit the valve to rest thereon, and the spring-arms will prevent the ball-valve from leaving the neck of the bottle, as before explained.

60 It will be seen that the antirefilling bottle is exceedingly simple and inexpensive in construction, that it is positive and reliable in operation, and that it will effectually prevent the introduction of a liquid into a bottle after the latter has received its original contents. 65 It will also be apparent that the bottle will be absolutely worthless after its original contents have been decanted, that it cannot afterward be used in trade, and that the interior rib is readily constructed by grooving or 70 constricting the neck of the bottle when the glass is in a heated condition. Furthermore, it will be apparent that the parts are readily 75 assembled after a bottle has been filled.

75 Changes in the form, proportion, and minor details of construction may be resorted to without departing from the spirit or sacrificing any of the advantages of this invention.

80 What I claim is—

85 A non-refillable bottle provided within its neck portion with an annular rib 3 having oppositely-inclined upper and lower faces, the upper face being ground to constitute a valve-seat and the lower face forming a stop for the valve, a ball-valve or stopper consisting of a glass sphere having a single piece of spring-wire bent centrally to form a U-shaped connecting portion 9 secured within the ball, parallel portions 7 projecting outward from said ball to permit limited movement to the valve, and the terminal ends of said wire being bent oppositely outward and then inward

to form the spring-stops 7^a, said valve being
designed for insertion within the neck of the
bottle, and the wire arms to be pressed inward
to pass the rib 3 to permit a limited move-
ment when the bottle is tipped and prevent
removal of the valve, substantially as de-
scribed.

In testimony that I claim the foregoing as
my own I have hereto affixed my signature in
the presence of two witnesses.

CEPHAS GILBERT.
